UNITED STATES PATENT OFFICE.

BANCROFT G. BRAINE, OF NEW YORK, N. Y., ASSIGNOR TO THE RAIL JOINT COMPANY,
A CORPORATION OF NEW YORK.

PROCESS FOR MAKING STEP-JOINTS.

1,394,708.

Specification of Letters Patent. Patented Oct. 25, 1921.

Application filed November 5, 1919. Serial No. 335,872.

To all whom it may concern:

Be it known that I, BANCROFT G. BRAINE, citizen of the United States, residing at New York, in the county of New York and State 5 of New York, have invented certain new and useful Improvements in Processes for Making Step-Joints, of which the following is a specification.

This invention relates to the manufacture 10 of step joints and more particularly to a process available for use in connection with rolled joint bars, thereby utilizing the advantages of rolling mill practice as well as simplifying the production of stepped bars 15 to meet the various combinations of rails of different sizes and sections to be connected.

Heretofore, in the making of step joints for connecting rails of dissimilar section it 20 has been the general practice to construct the same of steel or malleable iron castings, and of a design and configuration corresponding to the rail sections to be united. It has also been proposed to roll step joint 25 bars with the aid of specially designed rolls which must be made at a great expense to meet the particular sizes of the rails to be connected. However, the relatively few and varying combinations of step joints employed render production by the rolling method costly on account of the investment 30 in equipment and it is therefore desirable to provide means whereby step joint bars may be made to suit varying requirements in a 35 simple and practical manner and still preserve the advantages of a rolled bar.

Accordingly, the present invention primarily has in view a novel process whereby a rail joint bar having a uniform section 40 throughout may be readily made to fit both the larger and smaller rail in a thoroughly practical and efficient manner with a minimum of expense and without sacrificing any of the structural features of the bar.

To that end the invention particularly contemplates a process which utilizes a standard rail joint bar suitable for a rail of one size to provide in a simple and practical way for deforming or reshaping the 45 bar by a bull-dozing or equivalent operation to fit the smaller rail and in carrying forward that object the invention consists of a process which involves an economical use of the bar without change in the original 50 distribution of the metal, thereby preserving

all of the features and advantages incident to the type of bar which is selected for making the step joint.

Various instrumentalities may be utilized in carrying out the present invention, and 60 various means may be employed in handling the bar during the course of its development. Therefore, the accompanying drawings more or less diagrammatically indicate the steps involved in carrying the process 65 into effect by illustrating the joint bars in the different stages of their development.

Figures 1 and 2 are respectively outside and inside perspective views of a joint bar of the continuous type having a vertical 70 kerf for permitting the vertical deformation of one end of the bar to accommodate bars of different section and weight having the same fishing space.

Fig. 3 is a side elevation of the undeformed joint bar shown in Fig. 1 applied to rails of different section having the same 75 fishing space.

Fig. 4 is a perspective view of the bar shown in Fig. 3 deformed or reshaped as a 80 finished step joint bar.

Fig. 5 is a perspective inside view of an undeformed joint bar provided with longitudinal kerfs which permits of a deformation adapting the bar to connect dissimilar 85 rails having different fishing spaces.

Fig. 6 illustrates the bar of Fig. 5 applied to rails having different fishing spaces in its final shape with the vertical and horizontal easement kerfs welded. 90

Figs. 7 and 8 are outside perspective views showing plain angle bars provided with vertical and horizontal easement kerfs for fitting rails having different fishing spaces, respectively before and after the deforming 95 operation.

Similar reference numerals designate corresponding parts throughout the several figures of the drawings.

In carrying the invention into effect it is 100 proposed to utilize a rolled joint bar of standard cross section and design adapted to fit the largest of the two rails which are to be connected, and adapted to have one end portion thereof operated upon by suitable instrumentalities whereby it may be deformed horizontally to fit the smaller rail where the rails have the same fishing space or reduced in vertical height to accommodate rails of different section and having 105 110

different fishing spaces. Thus, with the present process it is possible to use standard rolled rail joint bar shapes for the purpose of making step joints to connect rails of 5 different section.

In the making of step joints one of the necessary factors to be taken into consideration is the height of the fishing space of the rails to be connected. If the rails are of 10 different section but have the same fishing space it is only necessary to horizontally offset one entire end portion of the bar to properly engage the smaller rail. However, when it is necessary to accommodate the 15 bar to dissimilar rails having fishing spaces of different height it is necessary also to reduce the height of the web as well as elevate the head of the bar and draw the foot and base flanges thereof upwardly to provide 20 the necessary step for engaging the base of the smaller rail.

By way of illustration, reference is made to Fig. 1 of the drawings. In this figure of the drawings there is shown a continuous 25 type of joint bar A, that is, a bar having formed with the foot flange thereof a rail supporting base member B, though it will be understood that the invention is not limited in its application to a base supporting 30 type of joint bar but is clearly available for making a step joint bar from any of the conventional forms of splice bars employed in connecting rails. Regardless of the type of bar which is subjected to the steps of the 35 improved process the initial step in the performance of the process is to form in the bar what may be termed an easement kerf or slot which permits of a bull-dozing or bending operation to produce the necessary stepping in the intermediate part of the bar 40 without imposing or focusing undue strain on the metal fibers at such location. This is specifically illustrated in Fig. 1 of the drawings which illustrates the bar as being 45 pierced by a vertical kerf or slot designated by the numeral 1, which in the illustration of Fig. 1 is shown as extending from the junction of the head of the bar with its web, down vertically through the web and foot of 50 the bar into the base member B of the latter, this being more clearly shown by reference to Fig. 2 of the drawings. It will be obvious that the easement kerf 1 may be produced by a saw, punch or other cutting implement and provides a bending easement for 55 the bar whereby one end portion thereof may be bent out of alignment or stepped vertically from the other part of the bar, so that the same may be adapted for dissimilar rails 60 having the same height of fishing space.

The bending or displacing horizontally of the bar to form the step is preferably performed by what is known as a bull-dozing operation which may be readily accom- 65 plished by placing the entire bar in a bull-

dozing press and subjecting the same to the necessary deforming pressure. The joint bar, therefore, emerging from the second step of the process is offset or stepped to accommodate the dissimilar rails having the 70 same fishing space, and as a final step of the operation it is proposed to obliterate the slot or kerf, by means of welding, as indicated at 2 whereby the finished step joint bar will present a homogeneous structure throughout and its structural features and characteristics preserved in the finished product. Also it will be observed that the improved process provides means for connecting two dissimilar rails with a bar 75 heavier than could be readily bull-dozed without the kerfs or slots, and after the closing of the kerf or kerfs by the welding operation the joint will be substantially as strong as before the slots or kerfs were cut 80 into the bar.

In carrying the process into effect with a joint bar of uniform section to fit dissimilar rails having different fishing spaces it is necessary to provide one end portion of the 90 bar with horizontal kerfs which may be used with or without the vertical kerf, whereby the height of the web may be reduced or contracted as well as permitting the stepping or raising of the head and base 95 of the bar vertically to contact respectively with the underside of the rail head and with the base of the smaller rail. Accordingly, the novel step of the present process which proposes to initially form the bar with an 100 easement kerf or kerfs may be carried out in connection with a bar intended to fit dissimilar rails having different fishing spaces as shown in Figs. 5 and 6 of the 105 drawings.

In said figures the joint bar A' is provided with horizontal kerfs 5 and 6 which extend from one end of the bar to its medial portion, thus leaving an opening in the central part of the web W of the bar A' and 110 also disconnecting the foot flange 7 from the base 8 for the desired distance to enable the said base to be bent upwardly by a bull-dozing operation into the plane of the base of the smaller rail. It will therefore be 115 understood that after the initial step of forming the kerfs in the bar, the same is subjected to a bull-dozing operation to close up the easement spaces provided by the kerfs 5 and 6 which reduces the height of 120 the web of the bar to meet the smaller fishing space of the smaller rail and also dis- places one end of the bar upwardly to provide a stepped base 8^a and a stepped head portion 9. (Fig. 6.) This particular kerfing 125 of the bar may also be utilized in combination with the vertical kerf 1^a as shown in Fig. 5. These kerfs are finally welded as at x.

In forming bars for the gage side of the 130

- rails when the fishing spaces and the rail heads are of the same depth it will be apparent that it is only necessary to vertically offset or step the bar to properly support the 5 rails of different section, since the gage side and top of the dissimilar rails must be in alinement. However, in forming the bars for the opposite or outer side of the bar it is usually necessary to offset one end of the 10 bar horizontally as well as vertically. This horizontal offsetting may be readily accomplished by reason of the provision of the vertical slot or kerf in the bar since the horizontal offsetting occurs at substantially the 15 same point as the vertical offsetting which is made possible through the provision of the vertical easement kerf 1. A fundamental feature of the present process is therefore the provision of easement slots in the 20 bar at such points that either vertical or horizontal bending may be facilitated without weakening or fracturing the metal remaining in the zone of the bend, while at the same time this easement may be utilized in 25 the form of horizontal kerfs for diminishing the height of the bar to connect rails having different fishing spaces. The vertical easement slot or kerf therefore assists in the operation of providing bars for both 30 the gage and opposite side of the rail, or "rights" and "lefts" as they are known in the art.
- By way of further exemplifying the application of the improved process reference 35 is made to Figs. 7 and 8 of the drawings which show a plain angle bar C transformed into a step joint bar by means of the present process. This may be readily accomplished by providing the angle bar at intermediate 40 portions with a vertically disposed easement kerf 10 piercing the web of the bar and the foot flange thereof which permits ready bending or bull-dozing of one end portion of the bar upwardly to fit the smaller rail, 45 and, to adapt such a bar for a smaller rail with a smaller fishing than the larger rail, it will be only necessary to provide the bulldozed end of the angle bar with a longitudinally extending or horizontal kerf 11 which 50 permits the height of that end of the angle bar to be reduced or narrowed to fit the smaller fishing space. After these operations have been performed the kerfs or slots are closed by welding as indicated at y. 55 The "outside" bars are shown in these figures.
- From the foregoing it will be apparent that the present process contemplates the utilization of a standard joint bar for the purpose of making a step joint by a series of 60 novel steps which are characteristic of the invention. These steps involve first the cutting or slotting of the bar in such a manner as to provide bending easement, whereby when the bar is subjected to a bull-dozing 65 operation as the next step of the process it
- may be bent into the desired stepped formation. As a final step of the process it is proposed to weld the slits which result from the closing or partially closing of the cuts or kerfs to provide a homogeneous or solid bar 70 whose strength remains unimpaired. Also the improved process permits of the use of a much heavier bar section than ordinarily.
- It is thought that the essential features and advantages of the herein described 75 process will now be readily understood by those familiar with the art without further description, and it will also be understood that so long as the essentials are preserved, variations may be made and the manner of 80 carrying out the process to meet varying conditions and requirements of use.
- I claim:—
1. The process for making a stepped bar for rail joints which consists first in slotting 85 a part of the bar producing along the line of the slot a bending easement, and subsequently pressing into stepped relation the portion of the bar at opposite sides of the slot. 90
  2. The process for making a stepped bar for rail joints which consists first in cutting a bar along the line of bend to form a bending easement in such part of the bar, and subsequently applying a bending pressure 95 at one side of the cut part to bring the opposite portions of the bar into stepped relation. 100
  3. The process for making stepped joint bars which consists in first slotting a portion 105 of the bar, producing a bending easement along the line of the slotting, then applying a deflecting pressure at one side of the slotted part, and subsequently welding the bar in the zone of the slotted portion. 110
  4. The process for making stepped joint bars which consists in slotting an intermediate part of the bar by forming a vertical kerf therein producing a bending easement, and subjecting the bar at one side of the kerf to a deflecting pressure. 115
  5. The process for making stepped joint bars which consists in slotting an intermediate part of the bar by forming a vertical kerf therein producing a bending easement, then subjecting the bar at one side of the kerf to a deflecting pressure, and subsequently welding the kerfed part of the bar. 120
  6. The process for making stepped joint bars which consists in slotting a joint bar of uniform section throughout, and subsequently subjecting one end of the bar to a deflecting pressure at one side of the zone of the slot to thereby bring the opposite portions of the bar into stepped relation. 125
  7. The process for making stepped joint bars which consists in slotting a joint bar of uniform shape throughout, then applying a deflecting pressure at one side of the slotted part to thereby bring the opposite por- 130

tions of the bar into stepped relation, and subsequently welding the bar at the slotted portion.

8. The process for making stepped joint bars which consists in slotting an intermediate portion of the bar by a vertical kerf and also providing a longitudinal kerf therein, and then subjecting the bar at one side of both of said kerfs to deflecting pressure.

10 9. The process for making stepped joint bars which consists in slotting an intermediate portion of the bar by a vertical kerf and also providing a longitudinal kerf therein, then subjecting the bar at one side of both 15 of said kerfs to deflecting pressure, and subsequently welding the bar in the zone of the kerfs.

10. The process for making stepped joint bars which consists in subjecting a bar of 20 uniform section throughout to a slotting operation which provides kerfs arranged at right angles, then subjecting the kerfed portion of the bar to deflecting pressure and subsequently welding the bar in the zone of 25 the kerfs.

11. The process for making stepped joint bars which consists in slotting the web of the bar with a plurality of longitudinal kerfs, and then subjecting said bar to 30 forming pressure exerted in a line parallel to the vertical axis of the web of the bar.

12. The process for making stepped joint bars which consists in slotting the web of the bar with a plurality of longitudinal

kerfs, and then subjecting said bar to de- 35 forming pressure exerted in a line parallel to the vertical axis of the web of the bar, and subsequently welding the bar in the zone of the kerfs.

13. A process for making a stepped bar 40 for rail joints which consists in longitudinally slotting the web and foot portions of the bar, subsequently subjecting the slotted portions of the bar to a deflecting pressure exerted in a direction at right angles to the 45 slots and subsequently producing welds along the lines of the slots.

14. A process for making stepped bars for rail joints which consists in forming slots in the bar, then subjecting the bar to a bending 50 pressure to thereby bring separate portions of the bar into stepped relation and finally welding the bar along the line of the slot or slots.

15. A process for making stepped joint 55 bars which consists in first slotting a portion of the bar, then applying a deflecting pressure at one side of the slotted part to thereby bring separate portions of the bar into stepped relation, and subsequently obliter- 60 ating the slot by a weld.

In testimony whereof I hereunto affix my signature in the presence of two witnesses.
